ADJUSTABLE SPOUT AND CAP DEVICE FOR
THE SEALING AND DROPOWISE DISPENS-
ING OF FLUIDSRichard W. Mahoney, Elizabeth, N. J., assignor
to Merck & Co., Inc., Rahway, N. J., a corpora-
tion of New Jersey

Application September 13, 1949, Serial No. 115,349

6 Claims. (Cl. 222—422)

1

This invention relates to a device for controlling and regulating the dispensing of liquids and particularly to a device of the class described having means for forming drops of liquid in the dispensing thereof and for regulating the rate of formation of such drops. More particularly, the invention relates to a fluid discharge spout and cap combination wherein the cap includes drop forming means and means cooperating with the spout for selectively controlling and preventing the flow of fluid therefrom.

It is customary to distribute fluids including volatile materials such as lighter fluid, ether for anesthesia and the like in containers having a fixed or detachable spout tip for dispensing such liquids. These spout tips are normally fashioned from a soft metal such as lead or a lead alloy and have a restricted aperture at the discharge end or rupturable means for forming a restricted aperture. They are also generally provided with a detachable cap forming means for closing the discharge end of the spout to prevent unintended evaporation or spillage of liquid. In the use of these conventional dispensing spouts, particularly in the dispensing of volatile fluids, it is difficult to control the rate of discharge of the fluid and it is virtually impossible to discharge fluid at a uniform discharge rate. This is a serious disadvantage in the administration of volatile liquid anesthetics such as ether. It is also a serious inconvenience and something of a fire hazard in the more extensive use of spout tip containers of lighter fluid for filling cigarette lighters and the like.

An object of my invention is to provide an improved spout tip and cap construction wherein the cap includes means for dispensing fluid in the form of individual drops and wherein the spout and cap together form means for regulating the rate of forming drops of fluid; a further object of my invention being to provide a spout tip fashioned from resilient plastic material and having in the discharge end thereof an aperture adapted to be gradually restricted to a fully closed position by the bearing action of the cap against said discharge end. A still further object of my invention being to provide a screw engagement between the spout tip and cap facilitating gradual advancement from the cap along the spout tip to provide bearing engagement with the discharge end thereof.

These and other objects of my invention will be more fully understood from a consideration of the following description and accompanying drawing wherein the various parts of my device

2

have been identified in each of the views by suitable reference characters and wherein:

Fig. 1 is an exploded view, partially in section, showing my improved spout tip and cap construction applied to one conventional type of container;

Fig. 1A is a fragmentary sectional view showing the assembled relationship of the container and spout tip as shown in Fig. 1.

10 Fig. 2 is an enlarged detailed view of the discharge end of my spout tip and cap showing the discharge aperture of the spout tip in the fully open position;

Fig. 3 is a view similar to Fig. 2, showing the 15 discharge aperture of the spout tip in the fully closed position; and

Fig. 4 is a view similar to Figs. 2 and 3, showing the spout tip partially closed and arranged in an operating position to indicate the drop forming action of the reservoir and aperture in the cap.

In the drawing I have shown in Fig. 1 an exploded view of one adaptation of my device wherein the spout tip 10 and cap 11 are employed 25 in conjunction with a bottle 12 and cap 13 having an aperture 14 for receiving the shank of the spout tip 10. In this adaptation of the device, the spout tip 10 is provided with a double flanged mounting end wherein the first flange 15 is adapted to bear against the inner surface of the cap 13 adjacent the aperture 14 and the second flange 16 of the larger diameter is adapted to be flexed into seating engagement between the inner surface 17 of the cap 13 and the lip 18 of the bottle 12 to provide a fluid-seal therebetween as indicated in Fig. 1A. In the drawing the bottle 12 and cap 13 have been shown as having a threaded means for detachable engagement. It is to be understood, however, that any suitable detachable or permanent engagements between the cap 13 and bottle or container 12 can be provided.

It is to be understood that the adaptation of my device shown in Fig. 1 is merely illustrative of one practical application of my improved spout tip and cap construction. The spout tip can be employed in conjunction with any source of fluid and not necessarily in conjunction with a bottle or other container. Thus, for example, the spout tip and cap can be employed in a fluid feed line in the laboratory in place of the usual glass stop-cock for control of the rate of dispensing of fluids.

The details of my improved spout tip and cap construction are more clearly indicated by the 55 enlarged showings in Figs. 2, 3 and 4 of the

drawing. The spout tip 10 is of hollow or tubular and preferably tapered construction and is fashioned from a plastic material having sufficient body to be rigid and yet sufficient elasticity to permit flexure under applied pressure. Suitable plastic materials include: ethylene polymers, haloethylene polymers, vinyl polymers and copolymers, natural rubbers, synthetic rubbers, alkyd resins, polyesters, polyamides, styrene copolymers, celluloses, silicones.

The dispensing end 19 of the spout tip is of frusto-conical contour having a more convergent taper than the main shank of the spout tip 10 and terminating in a closed end wall 20 which is provided with a V-shaped cut extending into the dispensing end 19 to provide a discharge opening 21. The outer surface of the discharge end 19 is provided with means as indicated by the screw threads 22 for engaging cooperating means as indicated by the threads 23 on the cap 11.

The cap 11 is provided with a generally cylindrical portion 24 having a knurled or roughened surface facilitating relative rotation between the cap and spout tip. Integral with the cylindrical portion the cap is also provided with a conically tapered portion 25 preferably terminating in a rounded discharge end or tip 26 having a reduced aperture 27 therein. Inwardly of the aperture 27 is a chamber of reservoir 28 registering therewith and having a considerably larger diameter. The reservoir 28 forms a means for retaining a quantity of fluid 29 for dispensing through the aperture 27 in the form of drops 30, as indicated in Fig. 4 of the drawing. Adjacent the reservoir 28 the inner wall of the cap 11 is provided with a frusto-conical bearing surface 31 having a greater degree of taper than the frusto-conical discharge end 19 of the spout tip. In advancing the cap 11 on the spout tip 10 by relative rotation therebetween the end 20 of the spout tip engages the bearing surface 31 and by further advancing of the cap 11 the bearing surface 31 acts to constrict the end 20 of the spout tip so that the discharge opening 21 is gradually closed from the fully open position shown in Fig. 2 to the partially closed position shown in Fig. 4 and finally to the fully closed position shown in Fig. 3. The bearing surface 31 should preferably be of sufficient length to engage the discharge end 19 of the spout tip through the entire depth of the cut out forming the discharge opening 21 when in the fully closed position in order to ensure complete sealing of the spout tip.

It will be understood that in the adaptation of the device shown in Fig. 1 the container 12 can be held in one hand and the cap 11 rotated by the fingers of that hand to regulate the size of the discharge opening 21 of the spout tip, thereby regulating the rate of feed of the liquid to the reservoir 28 and correspondingly regulating the rate of formation of drops 30 as shown in Fig. 4. It is of particular advantage in the dispensing of highly volatile liquids such as ether where the heat of the hand is normally sufficient to cause the liquid to spurt from the conventional discharge spouts in an uncontrollable stream. With my device the reservoir 28 serves to retard such a stream and permit the regulated dispensing of ether or other liquids in form of discrete drops. The rate of forming of the drops can be slowed down or speeded up by slight rotation of the cap 11 on spout tip 10.

The cap 11 can be fashioned of any hard ma-

terial such as metal or relatively non-elastic plastic material such as phenolics, amino resins; furan resins, silicones, alkyd resins, polyester resins, polyamides, acrylics, ethylene polymers, haloethylene polymers, hard rubbers, vinyl polymers, styrene polymers, celluloses, casein and protein plastics, cold molded and inorganic plastics.

While in the drawing the discharge opening 21 of the spout tip has been shown as a single V-shaped cut transversely of the end 20 of the spout tip, it will be understood that this can also be considered as two cuts circumferentially spaced 180° apart. If desired, the device can be fashioned with three cuts spaced 120° apart or even with four cuts spaced with 90° apart. In each event the constricting action of the bearing surface 31 of the cap on the cut end of the spout tip 10 will operate in a similar way to gradually compress the end of the spout tip in moving the cap from the fully open position shown in Fig. 2 to the fully closed position shown in Fig. 3.

These and other modifications of my device will occur to those skilled in the art and to the extent that such modifications are embraced by the appended claims, and it is to be understood that they are part of my invention.

I claim:

1. A fluid dispenser comprising a tubular spout tip of resilient material and a cap member having a threaded engagement with said spout tip to provide longitudinal movement of the cap on said spout tip in the rotary movement thereof, said cap having a restricted fluid receiving chamber extending beyond the innermost point of longitudinal movement of said spout tip, the free end of said cap having a restricted discharge opening registering with said fluid receiving chamber, and cooperating means on said spout tip and on the inner surface of said cap between said chamber and the threaded portion of said cap for regulating the flow of fluid from said spout tip to said chamber.

2. A fluid dispenser comprising a tubular spout tip of resilient material and a cap member having a threaded engagement with said spout tip to provide longitudinal movement of the cap on said spout tip in the rotary movement thereof, said cap having a restricted fluid receiving chamber extending beyond the innermost point of longitudinal movement of said spout tip, the free end of said cap having a restricted discharge opening registering with said fluid receiving chamber, cooperating means on said spout tip and on the inner surface of said cap between said chamber and the threaded portion of said cap for regulating the flow of fluid from said spout tip to said chamber, and said last-named means comprising a discharge opening in the end of said spout tip and a bearing surface within said cap registering with the end of said spout tip and adapted to flex the end of said spout tip and gradually close the discharge opening therein as the cap is advanced longitudinally over said spout tip.

3. A fluid dispenser comprising a tubular spout tip of resilient material and a cap member having a threaded engagement with said spout tip to provide longitudinal movement of the cap on said spout tip in the rotary movement thereof, said cap having a restricted fluid receiving chamber extending beyond the innermost point of longitudinal movement of said spout tip, the free end of said cap having a restricted discharge

opening registering with said fluid receiving chamber, the end of said spout tip being slotted to provide a discharge opening therein, means within said cap adjacent said chamber forming a tapered bearing surface adapted to engage the slotted end of said spout tip and to gradually flex the same from a fully open position to a fully closed position in the longitudinal movement of the cap on said spout tip.

4. In combination with a fluid dispensing spout having a fluid discharge opening formed by a plurality of circumferentially spaced resilient members adapted to be flexed in restricting and closing said discharge opening, a cap device having a threaded engagement with said spout, means within said cap device, beyond the end of said spout in the closed position thereof, forming a fluid reservoir therein, the free end of said cap having a restricted drop forming aperture registering with said reservoir, and bearing means within said cap device between the threaded portion thereof and said reservoir adapted to flex the spaced members on said spout in controlling the flow of fluid from said spout to said reservoir.

5. In combination with a fluid dispensing spout having a fluid discharge opening formed by a plurality of circumferentially spaced resilient members adapted to be flexed in restricting and closing said discharge opening, a cap device having a threaded engagement with said spout, means within said cap device, beyond the end of said spout in the closed position thereof, forming a fluid reservoir therein, the free end of said cap having a restricted drop forming aperture registering with said reservoir, and bearing means within said cap device between the threaded por-

tion thereof and said reservoir adapted to flex the spaced members on said spout in controlling the flow of fluid from said spout to said reservoir, said bearing means being of frusto-conical contour.

6. In combination with a fluid dispensing cap having a drop forming aperture at one end thereof, an internally threaded portion at the other end thereof, a fluid reservoir registering with said aperture, and a frusto-conical bearing surface extending from said reservoir to the threaded portion of said cap, a tapered tubular spout of pliable material having means at the larger end thereof for registering with a source of fluid and means adjacent the other end thereof providing threaded engagement with said cap, the portion of said end protruding beyond said last named means having a greater degree of taper than the remainder of said spout and terminating in a flat end wall portion, a plurality of circumferentially spaced V-shaped cuts traversing said flat end wall forming a discharge passage in said spout, and the portions of the spout end intermediate said cuts engaging the bearing surface of said cap for restricting and closing said discharge passage as the spout is advanced into said cap by the threaded engagement therewith.
